**RECLOSABLE DISPENSING CONTAINER WITH
BUCKLE LOCK**

Stanley R. Koolnis, New York, N.Y., assignor to Lee Drechsler, Palisades, and Fred Zandell, New York, N.Y.

Filed Oct. 12, 1965, Ser. No. 495,272
5 Claims. (Cl. 229—17)

ABSTRACT OF THE DISCLOSURE

This invention relates essentially to a box including a top wall comprising an inner and an outer panel adhesively secured together at discrete locations, a pour opening in the inner panel which becomes exposed upon raising a portion of the top panel and means for reclosing said opening by holding said portion of said top panel in closing relationship.

This invention relates generally to containers, and is especially concerned with a unique box construction adapted for distribution of premiums.

As is well known to those versed in marketing, the distribution of premiums, say in the form of cash refund, or otherwise, is a highly desirable sales incentive. However, practical difficulties have been encountered in conventional modes of premium distribution, as by external attachment to the container of a premium or redeemable coupon, in that the premiums or coupons are frequently removed before the goods reaches the ultimate purchaser. Merely placing the premium or coupon in the contents of the container is not always sanitary, often results in inadvertent loss by the user, or presents inconvenience in redemption.

Accordingly, it is an important object of the present invention to provide a container construction for direct distribution of premiums which overcomes the above-mentioned difficulties, effectively protects the premium from inadvertent loss at any time or unauthorized removal prior to ultimate sale, affords separation of the premium from the contents of the container, and assures easy and convenient removal by the ultimate purchaser.

It is a further object of the present invention to provide a box construction having the advantageous characteristics mentioned in the preceding paragraph, which may be economically manufactured, set up and filled by existing equipment, conveniently shipped and stored in a flat, knocked-down condition for economy of space, and which provides a staunch and sturdy container of neat and attractive appearance adapted to be manufactured and employed at a reasonable cost.

It is a further object of the present invention to provide a container construction of the type described which permits of quick and easy opening to define a dispenser for the contents of the container, and which may be readily and repeatedly reclosed and reopened, as desired.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a plan view showing a blank for a container in accordance with the teachings of the present invention;

FIGURE 2 is a top perspective view showing a com-

2

pleted box of the present invention in its closed condition;

FIGURE 3 is a perspective view similar to FIGURE 2, but illustrating the box in an open condition;

FIGURE 4 is a partial sectional view taken generally along the line 4—4 of FIGURE 2;

FIGURE 5 is an enlarged partial perspective view illustrating the opened box of FIGURE 3 in a reclosed condition;

FIGURE 6 is a sectional view taken generally along the line 6—6 of FIGURE 5;

FIGURE 7 is a partial sectional view taken generally along the line 7—7 of FIGURE 6;

FIGURE 8 is an enlarged partial plan view of a blank for formation into a box of the present invention; illustrating a premium associated therewith; and

FIGURE 9 is a partial sectional view illustrating removal of the premium from the instant box.

Referring now more particularly to the drawings, and specifically to FIGURE 1 thereof, a blank is there generally designated 20, adapted to be formed into the container of the instant invention. The blank 20 may advantageously be formed of paper board or other suitably stiff, bendable material, being generally rectangular in overall outline configuration, and cut and scored to define a plurality of generally rectangular panels 21, 22, 23, and 24 arranged in side-by-side relation.

More particularly, the panel 21 is of generally rectangular outline configuration, being bounded at one side by edge 25, along its ends by score lines or folds 26 and 27 extending in parallelism from opposite ends of edge 25, and along its other side by a score line or fold 28 extending between scores 26 and 27 generally parallel to edge 25. The generally rectangular panel 22 is hingedly connected to the panel 21 by the fold line 28, being longitudinally coextensive therewith, and is bounded at one end by a fold line 29 in longitudinal extension of fold line 27. At the other end, panel 22 is bounded by an edge 30 in longitudinal extension of fold line 26; and, a longitudinal fold line 31 extends between the ends of fold 29 and edge 30 parallel to fold line 28.

The panel 23 is hingedly connected to the panel 22 by fold line 31, being longitudinally coextensive therewith, and is bounded at its opposite ends by a fold line 32 in longitudinal extension of fold line 29, and a fold line 33 in longitudinal extension of edge 30. The other side of panel 23 is bounded by a fold line 34 extending between adjacent ends of fold lines 32 and 33, in parallelism with fold line 31.

The remaining panel 24 is hingedly connected to panel 23 by fold line 34 and is bounded at its opposite ends by fold lines 35 and 36 respectively longitudinal extensions of fold lines 32 and 33. A side fold line or score 37 extends between adjacent ends of fold lines 35 and 36 in parallelism with fold line 34.

The panels 21 and 23 may be generally congruent to provide facing, spaced front and back walls, as will appear presently, while the panels 22 and 24 may be generally congruent to define side panels or walls of the erected container. In addition, a glue flap 38 is hingedly connected to and longitudinally coextensive with the fold line 37 of panel 24. Thus, upon swinging of the panels 21, 22, 23 and 24 about their hinged connections, the glue flap 38 may be adhesively secured to the panel 21 along edge 25.

Extending from the end fold 27 of panel 21 is an end panel 40, which may be of generally rectangular outline configuration. The end panel 40 is bounded within the fold line 27, parallel edges 41 and 42 extending from opposite ends of the fold line 27, and an edge 43 extending between the edges 41 and 42 generally parallel to the

fold line 27. The edge 43 may be provided with a half-moon cutout or notch 44.

A panel 46, of generally rectangular outline configuration similar to that of panel 40, may extend from fold line 26. The panel 46 is bounded within the fold line 26, edge 47 extending from one end of fold line 26 in alignment with edge 25, edge 48 extending from the end of edge 47 generally parallel to fold line 26, and fold line 49 extending from edge 48 to fold line 26 in alignment with fold line 28. The edge 48 may be provided with a semi-circular cutout 50, similar to the cutout 44, and an opening 51 may be formed in the panel 46 spaced within the bounds thereof and adjacent to fold line 49, as for retaining a premium and/or providing a dispensing outlet, as will appear more fully hereinafter.

Extending from the fold line 49, coextensive therewith, is an extension or flap 53. The extension 53 extends along edge 30 of panel 22, terminating generally medially of edge 30. A flap 54 extends from the opposite end score 29 of panel 22.

Extending from fold line 32 of panel 23 is a generally rectangular panel 55, similar to overall configuration to panel 40. The panel 55 is bounded within fold line 32, a pair of fold lines 56 and 57 extending from opposite ends of fold line 32 in respective alignment with fold lines 31 and 34, and an edge 58 extending between outer ends of fold lines 56 and 57 generally parallel to fold line 32. In addition, a pair of glue tabs, such as Van Buren ears 59 and 60 extend respectively from fold lines 56 and 57.

A generally rectangular panel 62 extends from the opposite fold line 33 of panel 23, and is generally of an outline configuration similar to that of panel 46. The panel 62 is bounded within the fold line 33, a pair of parallel fold lines 63 and 64 extending from opposite ends of the fold line 33 in respective alignment with fold lines 31 and 34, and an edge 65 extending between fold lines 63 and 64 generally parallel to fold line 33. Extending from the fold line 63 is a flap 66, providing a pull flap in the finished container, as will appear presently. The flap 66 may be coextensive with the fold line 63 and extend toward the extension 53. Further, the flap 66 may be formed with a medial fold line 67 in parallelism with the fold line 63, and provided with a generally semicircular cut 68 extending from the fold line 67 toward the fold line 63. That is, the convex side of the cut 68 is toward the fold line 63. The cut 68 and fold 67 combine to define a tab 69.

Formed in the panel 62, extending inwardly from the fold line 63 are a pair of generally parallel lines of weakness or perforation, while a fold line or score 72 extends between the inner ends of the perforate lines 70 and 71. As will appear more fully hereinafter, the portion 73 of panel 62 bounded within fold lines 63 and 72, and perforate lines 70 and 71, is severable along the perforate lines 70 and 71 for swinging movement about the fold line 72.

At the opposite end of panel 62, extending from fold line 64, is an additional glue tab or Van Buren ear 75. Also, a pair of flaps or tabs 76 and 77 extend from respective fold lines 35 and 36 of panel 24.

In addition to the above-described cuts and scores of blank 20, one surface of panel 46, the exposed surface in FIGURE 1, is provided in a region adjacent to opening 51, with a layer or coating of varnish, as at 78, or other suitably smooth, relatively impervious material. The coated region 78 may be spaced inward from fold line 26 and edge 48, extending inward from fold line 49 to and beyond opening 51. If desired, the coated region 78 may have one or more uncoated spots, as at 80. An additional region 81 of panel 22 may be similarly coated with varnish or the like, the region 81 extending from edge 30 inward a short distance, being spaced from fold lines 28 and 31.

The above-described blank 20 may be provided with adhesive on flap 38, and folded to secure flap 38 to panel 21 along edge 25. In this flat, folded condition the glued blank may be conveniently stored and shipped, ready for setup and filling operations.

Box erection is achieved by applying adhesive or glue to the undersurfaces of panel 55 with its adjacent ears 59 and 60, the undersurfaces of panel 62 with its adjacent flap 66 and ear 75, and the undersurface of extension 53, all as seen in FIGURE 1.

The box 85 of FIGURE 2 may then be erected by initially folding the flaps 54 and 76 inwardly, thence folding the panel 40 inwardly over the flaps 54 and 76, and then folding the panel 55 into facing adhesively secured engagement with the panel 40. The ears 59 and 60 are folded into facing adhesively secured engagement with the adjacent portions of panels 22 and 24. Thus, panels 21, 22, 23 and 24 define peripheral side walls, panels 21 and 23 defining the back and front walls, while panels 22 and 24 define the side walls.

The upper end or top wall, generally designated 86, of the box 85, is formed by swinging panel 46 inward over flap 77 and folding extension 53 downward along side wall 22. The panel 62 is then folded inward over panel 46, and the ear 75 and flap 66 folded downward along respective side walls 24 and 22.

By the coating applied to regions 78, 53 and 81, adhesive is not firmly effective, but rather provides a detachable or readily frangible adhesive securing. Thus, when the extension 53 is swung downward over the adjacent portion of side wall 22, only the outer side portions of extension 53 are firmly secured to the side wall 22, the intermediate region of extension 53 overlying coated region 81 being relatively free of the side wall 22. Similarly, when the adhesive-coated underside of panel 62 is swung into overlying facing engagement with panel 46, the severable portion 73 of panel 62 overlies the coated region 78 of panel 46 and is only frangibly secured to the latter. The spot securing achieved at spot 79 may be relatively firm, but readily manually detachable. Also, the adhesive-coated underside of flap 66 is only detachably secured in its facing engagement with extension 53, the spots 80 affording firm but detachable securing by manual pulling of the flap. As best seen in FIGURE 4, the flap 66 is bent into facing engagement with the extension 53, but spaced from the wall 22, so that the end of the flap remains free of the side wall and provides a finger pull.

Thus, it is only necessary to grasp the free end of flap 66 to detach the adhesive securing of the flap, and upon continued pulling, effect severance along weakened lines 70 and 71 to swing the portion 73 away from opening 51, the condition illustrated in FIGURE 3. This then exposes the opening 51 and permits the latter to function as a pouring or dispensing outlet. Reclosure is most conveniently and effectively achieved by returning the portion 73 to its position in closing relation with and over the opening 51 and engaging the semicircular flap portion 69 between the intermediate portion of extension 53 and adjacent portion of side wall 22. This condition is illustrated in FIGURES 5, 6 and 7.

In addition to the unique dispensing function of the container 85 described hereinbefore, the opening 51 may serve to receive a coin, token, or other premium 87, see FIGURES 8 and 9. The premium 87 may be removably retained in the opening 51 by any suitable means, as by a diametral tie 88 extending across the opening, which facilitates removal of the premium, as illustrated in FIGURE 9.

From the foregoing, it is seen that the present invention provides a container construction which fully accomplishes its intended objects and is well adapted to meet practical conditions of manufacture and use.

Although the present invention has been described in some detail by way of illustration and example for pur-

poses of clarity of understanding, it is understood that certain changes and modifications may be made within the spirit of the invention and scope of the appended claims.

What is claimed is:

1. A box construction comprising front, back and side walls hingedly connected together; a bottom wall extending between the lower ends of said front, back and side walls, and a top wall extending between the upper ends of said front, back and side walls; said top wall comprising an inner panel extending from one toward the other of said front and back walls; said inner panel having an opening adjacent to one side wall; an outer panel extending from the other wall toward said one of said front and back walls and overlying said inner panel in closing relation with said opening; and adhesive means firmly securing said inner and outer panels together except in a region adjacent to said opening; said outer panel being formed with a severable portion over said opening and said region for movement of said portion away from and exposing said opening; detachable adhesive means detachably securing said severable portion to said region; a pull flap extending from said severable portion beyond said one side wall; an extension on one side of said inner panel depending along said one side wall, additional adhesive means securing spaced portions of said extension to said one side wall to leave an intermediate portion of said extension free of said side wall, said pull flap being bendable downwardly to overlie said extension, and an inwardly extending catch tab on said pull flap removably

engageable between said intermediate extension portion and said one side wall.

5 2. A box construction according to claim 1, in combination with additional detachable adhesive means detachably securing said pull flap in overlying relation with said extension.

3. A box construction according to claim 1, in combination with a premium carried in said opening.

10 4. A box construction according to claim 1, said detachable adhesive means comprising a relatively impervious layer on one facing surface, and adhesive interposed between said layer and the other facing surface.

15 5. A box construction according to claim 3, wherein said detachable adhesive means detachably secure said severable portion to said region except in a second region adjacent to said premium.
